UNITED STATES PATENT OFFICE.

SAMUEL WALTERS, OF DALLAS CITY, ILLINOIS.

IMPROVEMENT IN CORN-STALK CUTTERS.

Specification forming part of Letters Patent No. 124,401, dated March 5, 1872.

To all whom it may concern:

Be it known that I, SAMUEL WALTERS, of Dallas City, in the county of Hancock and State of Illinois, have invented a new and valuable Improvement in Corn-Stalk Cutters; and I do hereby declare that the following is a full, clear, and exact description of the construction and operation of the same, reference being had to the annexed drawing making a part of this specification, and to the letters and figures of reference marked thereon.

Figure 1 of the drawing is a representation of a vertical longitudinal section of my invention; Fig. 2 is a top-plan view of the same.

This invention has relation to corn-stalk cutters; and the novelty consists in the construction and arrangement of devices for giving a vertical chopping motion to the knife, of devices for raising the knife above obstacles, and keeping it in a uniform position.

In the accompanying drawing illustrating this invention, A represents a rectangular frame mounted on two driving-wheels, B B'. C designates a spur-wheel secured to the rotating axle of the wheels B B', and turning with it. D represents a shaft holding a sliding pinion, E, which engages with the spur-wheel C and a crank-arm, D', which is coupled to a lever-arm, E', pivoted to one end of a rocking bar, F. G designates a frame hinged to the frame A. Secured to it is a bracket, H, to which the rocking bar F is pivoted and works on as on a fulcrum. The end of said bar, opposite the arm E', is coupled to a link, I, which supports a vertical rod, I'. The knife J is secured to the lower end of said rod in a horizontal transverse position, the cutting-edge below. The rod I' works through a guiding-

bracket, i, attached to and projecting from the middle longitudinal bar of the frame A. The vertical chopping motion of the knife is caused through the medium of the pinion and gear-wheel, acting through the intermediate devices referred to and described. K represents a clutch-arm pivoted to a bracket, K', and designed for the purpose of throwing the gear-wheel and pinion into and out of gear. L indicates a bell-crank pivoted underneath the inner end of the frame G. It is connected, by means of a rod, L¹, to a foot-lever, L², within reach of the driver's foot, M being the driver's seat. By pressing the lever L² forward the frame G may be raised so that the knife may pass over obstacles. One arm of the bell-crank should be curved so as to work against the under side of the frame G with ease. N designates a friction-roller for keeping the knife in a steady, even position, and prevent it from being thrown out of place by obstacles. Said roller is journaled to the end of a bent arm, N', extending back from the frame G, to which it is attached. O represents a pressure-roller, arranged in front of the knife. It is journaled to a pair of arms, P, hinged to the forward end of the frame A.

I claim as my invention—

The frame G hinged to the frame A and supporting the rocking-bar F, in combination with the bell-crank L, rod L¹, and foot-lever L², or other equivalent operating devices, substantially as specified.

SAMUEL WALTERS.
